Primary Examiner — Catherine S Posthauer(74) *Attorney, Agent, or Firm* — ScienBiziP, P.C.(57) **CLAIM**

The ornamental design for a straw cup lid, as shown and described.

DESCRIPTION

FIG. 1 is a front perspective view of a straw cup lid, showing my design.

FIG. 2 is a rear perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines immediately adjacent to the shaded areas depict the bounds of the claimed design, while all other broken lines illustrate portions of the straw cup lid. The broken lines form no part of the claimed design.

1 Claim, 8 Drawing Sheets(56)
